UNITED STATES PATENT OFFICE.

OSCAR L. GLASER, OF CHICAGO, ILLINOIS.

GOLF-BALL TEE.

Application filed August 27, 1927. Serial No. 215,874.

This invention relates to a golf ball tee or golf tee for supporting golf balls when driving from a tee or when playing winter rules.

5 The object of the invention is to provide a novel and simple golf tee formed of a single section of metal or wire in a continuous piece having a ball retaining portion or ring of square, polygonal or other 10 suitable shape at the top to support and retain the golf ball and having underneath, a plurality or pair of spiral turns providing a symmetrical appearance and also a spring for resiliency, as well as a shoulder to limit 15 the degree which the shank may be pressed into the ground and thus the height of the tee in use, so as to give a player a set height at all times.

With the above and other objects in view, 20 the invention consists of certain novel combinations and arrangements of parts to be hereinafter more fully described.

In the accompanying drawings

Figure 1 is a perspective view of a golf 25 tee or golf ball tee constructed in accordance with the invention.

Figure 2 is an elevation of the device showing the same in the ground for supporting a golf ball, and

30 Figure 3 is a top plan view of the golf tee.

Referring to the drawings in detail, in which like reference characters designate corresponding parts throughout the several views, it will be seen that the tee is formed 35 from a single section of ordinary spring or iron wire or a continuous strip of metal of suitable flexible character tinned, nickel, or otherwise coated to protect it from rust, the wire being indicated at 4. This wire is

40 of suitable gauge and has the shank portion 5 formed with a tapered or pointed end 6 to readily penetrate the ground. The top portion is provided with a square rectangular or other suitable ball retaining portion 7, the end 8 of the wire engaging the next adjacent corner or side designated at 9, although it is to be understood that said ball retaining portion may be of other polygonal

section, triangular, hexagonal, octagonal, or other suitable shape in addition to being 50 square or rectangular. The wire where bent from the point 9 is extended off in the curved direction at an angle inwardly and downwardly as designated at 10, being at an acute angle with respect to the side 11 of the ball 55 retaining portion 7 and then circled or formed with two complete coils or turns 12 and 13, the two circles being formed into a cone shape so as to give a symmetrical appearance and also produce a coil or spring, 60 the bottom of which at the point 14 forms a shoulder which will act as a stop when pressed in the ground giving the player a set height at all times for the ball supported on the ball retaining portion of the tee. The 65 tapered coil spring will also make the golf tee resilient and avoid bending of the shank and also limit the height which the shank is pressed into the ground so that there will be no objection to the use of a device as 70 ordinarily the case, in having the ball teed too high or too low, thus insuring that the player will always have the ball teed to the proper height and produce better shots. If the device is at all bent in use it may be readily 75 bent back into shape for re-use.

While I have described my invention and shown the tee in the preferred form, it is to be understood, as previously stated, that the ball retaining portion may be of other 80 shape and that I am not limited to the use of two turns or coils or in the exact formations described so long as such constructions do not depart from the spirit and scope of the invention as claimed.

Having thus described my invention, what I claim is:

A golf ball tee comprising a single piece of wire bent at one end into the form of a cup shaped receptacle for the ball, the upper 90 periphery of the cup being of square formation, the remaining portion of the cup being of spiral and conical form.

In testimony whereof I affix my signature.

OSCAR L. GLASER.
